SELECTIVE-POLE TRIPPING SYSTEM

Shirley L. Goldsborough, Basking Ridge, and
 John L. Blackburn, East Orange, N. J., assignors
 to Westinghouse Electric Corporation, East
 Pittsburgh, Pa., a corporation of Pennsylvania

Application November 28, 1947, Serial No. 788,582

3 Claims. (Cl. 175—294)

1

Our invention relates to a selective-pole tripping-system for protecting a three-phase transmission-line against faults by so controlling three single-pole circuit-breakers as to open only a minimum number of breakers, in the phases which are affected by a fault which involves less than all of the phase-conductors of the line.

Our invention is an improvement over, or a modification of, the selective-pole tripping-system which is described and claimed in the copending Goldsborough application Serial No. 569,181, filed December 21, 1944, in which only one breaker-pole is tripped on a phase-to-phase fault involving no ground-current, as this one breaker-operation is all that is necessary to interrupt the fault-current. According to the NEMA rules, where simultaneous tripping of all faulted poles is not assured, the breakers must have a voltage-rating equal to 115% of the rated circuit-voltage. However, many electric-power customers, who desire to install selective-pole tripping, have their systems already equipped with breakers which are rated at 100% of the rated circuit-voltage, and hence the use of the previously known selective-pole tripping-system, as shown in the copending Goldsborough application, would put these breakers outside of their guaranteed ratings.

The object of our present invention is to provide means for eliminating the single-pole operation on phase-to-phase faults, and obtaining two-pole operation, on these particular faults, while retaining the other features of the previous selective-pole tripping-system which is shown in the copending Goldsborough application.

With the foregoing and other objects in view, our invention consists in the circuits, system, apparatus, combinations, parts and methods of operation and use, hereinafter described and claimed, and illustrated in the accompanying drawing, the single figure of which is a very much simplified diagrammatic view of circuits and apparatus, illustrating only those elements and circuit necessary to an understanding of our present invention.

We have illustrated our invention as being applied to the protection of a three-phase transmission-line 1, which is connected to a bus 2 through three single-pole circuit-breakers CB—A, CB—B and CB—C, which are provided with trip-coils TC—A, TC—B and TC—C, and auxiliary make-contacts *aA*, *aB* and *aC*, respectively. The several line-phases are distinguished by the letters A, B and C.

As shown in the drawing, we use a distance-responsive and directionally responsive fault-

2

detector panel or box 3, which may be of any desired type, such as that which is shown in the Goldsborough Patent 1,934,662, granted November 7, 1933. It is illustrated as comprising a ground-directional relay-contact DO, three phase-fault directional-relay contacts DA, DB and DC, three phase-fault distance-relay contacts ZA, ZB and ZC, which are set to have a balance-point for faults just beyond the far end of the protected line-section 1, three contactor-switch contacts CSA, CSB and CSC which respond still more sensitively to phase-faults which are further out in the transmission-system, and an overcurrent ground-fault relay IO having one make-contact and three back-contacts. The fault-detector panel 3 is illustrated as being energized from a bank of line-current transformers 4 and from potential-transformers 5.

As shown in the drawing, we also use a phase-selector apparatus or panel 6, which is shown as providing three make-contacts and three back-contacts of three phase-selectors SA, SB and SC for selecting the phase which is involved, in the event of a single line-to-ground fault. These phase-selector relays may be of the construction shown in the Goldsborough Patent 2,320,861, granted June 1, 1943, involving a comparison between the negative and zero phase-sequence components of the line-currents which are supplied to the relays, as by means of a bank of line-current transformers 7.

As still further shown in the drawing, we also provide a carrier-current or other pilot-channel protective-relay equipment or panel 8, which is provided with two make-contacts RRG and RRP, one for the ground-fault tripping-circuit, subsequently described, and one for the phase-fault tripping-circuit. This carrier-current fault-detection relaying-equipment may be the distance-type of carrier-current system, such as is shown in the Lenehan et al. Patent 2,255,934, granted September 16, 1941, or the Blackburn et al. Patent 2,367,921, granted January 23, 1945, or a copending Lenehan application, Serial No. 599,832, filed June 16, 1945, now Patent No. 2,449,490, granted September 14, 1948. The carrier-current panel 8 is illustrated as being supplied with current from a set of line-current transformers 9, and voltage from the potential-transformers 5, and it is connected at 11 to a coupling-transformer 12 which is connected to the phase-C line-conductor C, on the line-side of a carrier-current trap 13.

In the drawing, we have shown only one terminal of the protected line-section 1, but it will be

understood that the other line-terminal is, or may be, a duplicate of the terminal equipment which is illustrated. Furthermore, while we have illustrated the several relay-panels 3, 6 and 8 as receiving their line-current energization from three separate banks of line-current transformers 4, 7 and 9, a single set of line-current transformers could be used for supplying the relaying currents for all three panels.

In the drawing, we also show a very much simplified diagrammatic representation of the essential direct-current tripping-circuits and their associated control-circuits or elements. In brief, it may be said that we have added, to the previously known selective-pole tripping-system of the copending Goldsborough application Serial No. 569,181, three auxiliary relays CSA', CSB' and CSC', and the three back-contacts of the overcurrent ground-fault relay IO.

The several relays are indicated by letter designations or legends, and the same letter-designation or legend is applied to the operating-coil and to all of the contacts of any given relay. The relays and switches are invariably shown in their open or deenergized positions. The relays for different phases or circuits are distinguished by suitable letters which are suffixed to the general relay-designation. Arrows are used, to symbolically indicate how the various parts of each relay are connected together.

As shown in the drawing, there are three tripping-circuits, TA, TB and TC, each of which consists of its own tripping-coil TC—A, TC—B or TC—C, as the case may be, and an auxiliary make-contact of its associated circuit-breaker, as indicated at aA, aB and aC, respectively. The end-terminals of these tripping-circuits TA, TB and TC are connected to the negative relaying-bus (—). There are two principal ways for energizing each of these three tripping-circuits TA, TB and TC, the first way being by way of a ground-fault relaying-circuit 15, which connects the carrier-current receiver-relay contact RRG to the positive relaying-bus (+), and the second way being by way of a phase-fault relaying-circuit 16, which connects the carrier-current receiver-relay contact RRP to the positive bus (+).

The ground-fault relaying-circuit 15 continues on, from the receiver-relay contact RRG, through the ground-directional make-contact DO and the overcurrent ground-relay make-contact IO, to a relaying-bus 17. From the relaying-bus 17, the ground-fault relaying-circuit separates into three branches, one for each phase. As the branches are similar, except for the lettering, it will suffice to describe the phase-A branch, which energizes the phase-A trip-circuit TA through the phase-selector make-contact SA, the phase-selector back-contact SC, and the contactor-switch back-contact CSB, the latter being shunted by the operating-coil CSX of an auxiliary relay CSX. This coil CSX has such a high resistance that it does not permit the flow of an adequate tripping-current when its bypassing contact CSB is opened. This auxiliary switch CSX has a make-contact CSX, which joins the other two tripping-circuits TB and TC to each other, for the purpose of securing two-pole tripping in the event of a double phase-to-ground fault, as more particularly described and claimed in the copending Goldsborough application Serial No. 569,181.

The phase-fault tripping-circuit 16 contains only the receiver-relay contact RRP, and is utilized to energize a relaying-bus 18, at which point the phase-fault relaying-circuit divides into three

branches, one for each phase. These branches are again similar, except for the lettering, so that it will suffice to describe the phase-A branch, which energizes the phase-A trip-circuit TA through the phase-fault directional-content DA, the phase-fault impedance contact ZA, and the operating-coil CSA' of the auxiliary relay CSA'. This operating-coil CSA' may have an impedance which is sufficiently low to permit the flow of an adequate tripping-current for energizing the phase-A trip-coil TC—A.

In accordance with our invention, each of the three auxiliary relays CSA', CSB' and CSC' has a correspondingly lettered make-contact which is used to join the trip-circuit of its phase to the trip-circuit of the next lagging phase. Each of these make-contacts, such as CSA', is connected in series with the back-contact of the corresponding auxiliary relay in the next leading phase, such as the CSC' back-contact, and in most cases it is also connected in series with one of the back-contacts of the overcurrent ground-fault relay IO.

In the operation of our invention, it will be necessary to describe only the novel features which are not shown in the copending Goldsborough application Serial No. 569,181.

The novel operation of our invention takes place upon the occurrence of an ungrounded phase-to-phase fault, which will be assumed to occur from phase-A to phase-B. The phase-A phase-fault relays DA and ZA respond to such a fault, and energize the phase-A trip-circuit TA through the carrier-current receiver-relay contact RRP, the DA contact, the ZA contact, and the CSA' coil. The auxiliary relay CSA' responds, and connects the phase-A trip-circuit TA to the phase-B trip-circuit TB, through the CSA' make-contact, the CSC' back-contact and the IO back-contact. The purpose of the CSC' back-contact is to prevent the tripping of all three poles in a case where a close-in phase-to-phase fault operates two phase-fault relays, such as DA, ZA, and DB, ZB. The DB and ZB contacts, in such a case, energize the CSB' relay, whose make-contact CSB' would energize the TC trip-circuit from the TB trip-circuit, except for the presence of the CSA' back-contact in series with the CSB' make-contact. The purpose of the IO back-contacts is to break up the circuit through the CSA', CSB' and CSC' make-contacts, in the event of faults which involve ground, so that our special two-pole tripping-operation occurs only for phase-faults which do not involve ground.

While we have described our invention in only a single illustrative form of embodiment, which has been very greatly simplified for facility in illustrating the novel features of the invention, we wish it to be understood that various changes may be made, by way of additions, omissions and substitutions, without departing from the essential spirit of our invention. We desire, therefore, that the appended claims shall be accorded the broadest construction consistent with their language.

We claim as our invention:

1. Fault-responsive protective relaying-means for controlling each of a plurality of single-pole circuit interrupters in the several phase-conductors of a three-phase line, comprising a pilot-channel relaying-means for obtaining a fault-responsive relay-operation under the supervision of pilot-channel intelligence received from the far end of the protected line-section, ground-fault phase-selector means for obtaining a phase-

selecting relay-operation in response to line-conditions obtaining in the event of a single line-to-ground fault, phase-fault phase-selector means for obtaining a phase-selecting relay-operation in response to line-conditions obtaining in the event of a phase-to-phase line-fault, said phase-fault phase-selector means being operative to reliably select only one of the two line-conductors which are involved in some line-to-line faults, ground-fault circuit-interrupter control-circuit means for controlling the selected phase of the single-pole circuit-interrupters in joint response to said pilot-channel relaying-means and said ground-fault phase-selector means, phase-fault circuit-interrupter control-circuit means for controlling the selected phase of the single-pole circuit-interrupters in joint response to said pilot-channel relaying-means and said phase-fault phase-selector means, and auxiliary interrupter-controlling circuit-means, associated with said phase-fault circuit-interrupter control-circuit means, for joining the control-circuit selected by a phase-fault selector-means to the control-circuit for a second line-phase, in response to a response of the phase-fault phase-selector means for the selected line-phase and a non-response of the phase-fault phase-selector means for the third line-phase.

2. Fault-responsive protective relaying-means for controlling each of a plurality of single-pole circuit-interrupters in the several phase-conductors of a three-phase line, comprising a pilot-channel relaying-means for obtaining a fault-responsive relay-operation under the supervision of pilot-channel intelligence received from the far end of the protected line-section, a ground-fault detector-means for responding to the occurrence of a ground-fault, ground-fault phase-selector means for obtaining a phase-selecting relay-operation in response to line-conditions obtaining in the event of a single line-to-ground fault, phase-fault phase-selector means for obtaining a phase-selecting relay-operation in response to line-conditions obtaining in the event of a phase-to-phase line-fault, said phase-fault phase-selector means being operative to reliably select only one of the two line-conductors which are involved in some line-to-line faults, ground-fault circuit-interrupter control-circuit means for controlling the selected phase of the single-pole circuit-interrupters in joint response to said

pilot-channel relaying-means and said ground-fault phase-selector means, phase-fault circuit-interrupter control-circuit means for controlling the selected phase of the single-pole circuit-interrupters in joint response to said pilot-channel relaying-means and said phase-fault phase-selector means, and auxiliary interrupter-controlling circuit-means, associated with said phase-fault circuit-interrupter control-circuit means, for joining the control-circuit selected by a phase-fault selector-means to the control-circuit for a second line-phase, in response to a response of the phase-fault phase-selector means for the selected line-phase, a non-response of the phase-fault phase-selector means for the third line-phase, and an non-response of the ground-fault detector-means.

3. Fault-responsive protective relaying-means for controlling each of a plurality of single-pole circuit-interrupters in the several phase-conductors of a three-phase line, comprising a pilot-channel relaying-means for obtaining a fault-responsive relay-operation under the supervision of pilot-channel intelligence received from the far end of the protected line-section, ground-fault phase-selector means for obtaining a phase-selecting relay-operation in response to line-conditions obtaining in the event of a single line-to-ground fault, phase-fault phase-selector means for obtaining a phase-selecting relay-operation in response to line-conditions obtaining in the event of a phase-to-phase line-fault, said phase-fault phase-selector means being operative to select both of the phases which are involved in any phase-to-phase fault, whether grounded or ungrounded, out to a point just beyond the far end of the protected line-section, ground-fault circuit-interrupter control-circuit means for controlling the selected phase of the single-pole circuit-interrupters in joint response to said pilot-channel relaying-means and said ground-fault phase-selector means, and phase-fault circuit-interrupter control-circuit means for controlling the selected phases of the single-pole circuit-interrupters in joint response to said pilot-channel relaying-means and said phase-fault phase-selector means.
